UNITED STATES PATENT OFFICE.

JOHN A. GOUCK, OF SCOTTSVILLE, NEW YORK.

DESIGN FOR A SAW.

44,561.

Specification for Design. **Patented Aug. 26, 1913.**

Application filed May 28, 1913. Serial No. 770,520. Term of patent 7 years.

To all whom it may concern:

Be it known that I, JOHN A. GOUCK, a citizen of the United States of America, residing at Scottsville, in the county of Monroe and State of New York, have invented a new, original, and ornamental Design for Saws, of which the following is a specification, reference being had to the accompanying drawing, forming part thereof.

The figure is a plan view of a saw showing my new design.

I claim:

The ornamental design for a saw, as shown.

JOHN A. GOUCK.

Witnesses:

JACOB GOUCK,
GOODARD J. FREIDELL.
